W. E. WINE

VENTILATION OF BOX CARS

Filed March 20, 1925

Patented Sept. 14, 1926.

1,599,451

UNITED STATES PATENT OFFICE.

WILLIAM E. WINE, OF TOLEDO, OHIO.

VENTILATION OF BOX CARS.

Application filed March 20, 1925. Serial No. 16,985.

My invention relates to new and useful improvements in the ventilation of box cars, and has for an object to so arrange the ventilators that a more perfect ventilation will be had than has heretofore been possible in railway freight cars.

As is well known to those skilled in the art, box cars that are ventilated are provided with a ventilator or ventilators in their opposite ends, and furthermore, the side doors of the cars are at times provided with a form of ventilating means such as an opening protected with bars, behind which is placed a netting; but there are certain disadvantages in ventilating a car in this manner, as will be pointed out.

When the doors are provided with a ventilating means, it, of course, adds expense to the cost of the doors, and due to the continual opening and closing of the doors, they wear, become jammed, are forced open, and thus wear out more quickly than the remainder of the car, and although the ventilator or ventilating means may be in perfect order, the door has to be discarded and the ventilator discarded with it.

Further, ventilators of the Wine type, or any ventilators having moving parts and shutters cannot be well installed in the doors, as it would mean that it would add increased weight to the door and the jar and slamming of the doors would soon damage the ventilator.

One of the principal objects therefore, of the present invention, is to cut openings in the opposite sides of the box cars and adjacent the doorways, and place ventilators within these openings, thus providing a staggered relation of the ventilators, which permits a more perfect ventilation to the interior of the car.

Still another object of the invention is to arrange two ventilators opposite the doorway on one side of the car one above the other, and two more ventilators in the relative same position but on the opposite side of the car and diagonally positioned with these first two mentioned ventilators.

Still another object of the invention is to arrange these ventilators opposite their respective doorways, and to also provide a ventilator in the opposite ends of the cars, thus providing a fine circulation of air throughout the entire interior of the car.

With these and other objects in view, the invention consists in certain new and novel

arrangements and combination of parts as will be hereinafter more fully described and pointed out in the claim.

Referring now to the drawings showing a preferred embodiment of the invention,

Fig. 1 is a side elevation of a box car showing the novel arrangement of the ventilators for maximum ventilation.

Fig. 2 is a horizontal sectional view taken on line 2—2 of Fig. 1.

Fig. 3 is a fragmentary sectional view showing a ventilator secured in the end of the car, and

Fig. 4 is a fragmentary sectional view showing the ventilator secured adjacent the door opening.

Referring now more specifically to the several views, there is shown a standard type of box car 1 having on its one side the door opening 2, and on its opposite side the opening 3, one door only being shown and drawn back to its open position.

As may be seen in Fig. 1, there are two ventilators 5 and 6 positioned opposite the door opening 2, these ventilators being arranged one above the other, and adjacent the door opening, and at the far side from the door when the latter is pulled to its open position.

These ventilators may be the "Wine type" ventilators, as shown in my Patent No 1,040,084 granted on October 1, 1912, or any of my later type ventilators, and in fact, may be ventilators of other types than the Wine ventilators. I mention especially the Wine type ventilators as it is one of my own products, but it will be strongly understood that any other good type of ventilator might be used.

As may be seen in Fig. 1, there is shown in dotted lines two more ventilators 7 and 8 which are located one above the other similar to the arrangement of the ventilators 5 and 6, but as may be clearly seen in Fig. 2, the ventilator 7 is diagonally opposite the ventilator 5, and the ventilator 8 will be diagonally opposite the ventilator 6.

There is a great advantage in having these ventilators in staggered relation, as it permits the air to circulate freely within the car, rather than passing in one side of the car and right out the opposite side, which would be the case if the ventilators were not in their staggered relation.

At the forward end of the car is shown a ventilator 9 (see Fig. 2) and at the rear end

of the car is shown a ventilator 10, and it will be understood that although I have only shown one ventilator in the opposite end, two might be employed in each end if desired.

In Fig. 3 there is shown an I-bar 11, with the bolt 12 and the small angle 13 for securing the ventilator 9 in place, while in Fig. 4 there is shown a slightly different arrangement for securing the ventilators to the uprights in the car but this manner of securing the ventilators does not form a part of the present invention.

As heretofore mentioned, the arrangement of the ventilators in staggered relation with each other and in the sides of the car adjacent the sides of the door opening, is far superior to a screened or barred opening in the respective doors, inasmuch as the air will more freely circulate throughout the interior of the car and thus provide a maximum ventilation, which is impossible where the ventilators are directly opposed to each other. Furthermore, the ventilators by being placed in the sides of the car rather than in the doors, are subject only to the shocks incident to the car as a whole, and not further subjected to the shocks that are incident to the doors by the opening and closing of the same. The doors may become worn, damaged or discarded and new ones replaced without in any way affecting the ventilators.

Again, by providing two ventilators, one

above the other, hot air may pass from near the top of the car at its central portion 35 while the cool air may pass in along the lower central portions of the car.

From the foregoing it will be seen that by arranging the end ventilators and side ventilators as shown, the car may be kept cool 40 or rather may be supplied with fresh air at all times and the circulation far superior to the circulation that is obtained in the cars with the ventilators, as now arranged.

I do not wish to be limited to the type of 45 ventilators shown, nor to the manner in which they are secured within the car, but what I do claim as new and desire to secure by Letters Patent is:—

A box car having door openings in its respective sides and two ventilators located one above the other on each of the respective sides adjacent the door openings and operable from the car floor, the ventilators on one side of the car being in staggered relation with the ventilators on the opposite sides of the car, a ventilator in both the opposite ends of said car cooperating with the staggered ventilators in the sides of the car, all of said ventilators being substantially 55 flush with the respective outer surfaces of the car, and the remaining portions of the side and ends of the car presenting substantially an unbroken surface.

In testimony whereof I affix my signature.
WILLIAM E. WINE.
